(57) **CLAIM**

I claim the ornamental design for picking apron, as shown and described.

DESCRIPTION

FIG. 1 is a front and right side isometric view of a picking apron showing my new design in use;

FIG. 2 is a front orthographic view thereof, with the front flaps in a secured position;

FIG. 3 is a left side orthographic view thereof;

FIG. 4 is a rear orthographic view thereof;

FIG. 5 is a right side orthographic view thereof;

FIG. 6 is a top plan view thereof;

FIG. 7 is a bottom plan view thereof; and,

FIG. 8 is a front orthographic view, with the front flap released.

The broken lines depict environment and are included for the purpose of illustrating only and form no part of the claimed design.
